UNITED STATES PATENT OFFICE

128,243

DESIGN FOR A LACE TRIMMING OR SIMILAR ARTICLE

Otto Hallbauer, West Englewood, N. J., assignor to Stein-Tobler Co. Inc., Union City, N. J., a corporation of New Jersey

Application April 28, 1941, Serial No. 190,652

Term of patent 3½ years

To all whom it may concern:

Be it known that I, Otto Hallbauer, a citizen of the United States, residing at West Englewood, Bergen County, and State of New Jersey,
have invented a new, original, and ornamental
Design for a Lace Trimming or Similar Article,
of which the following is a specification, reference being had to the accompanying drawing, forming part thereof, wherein—

The figure is a plan view of a lace trimming
or similar article, showing my new design.

I claim:

The ornamental design for a lace trimming or similar article, substantially as shown.

OTTO HALLBAUER.
